UNITED STATES PATENT OFFICE.

CHARLES W. LOGAN, OF KENMORE, NEW YORK, ASSIGNOR TO MARKEL LIGHTING FITMENTS, INC., OF BUFFALO, NEW YORK, A CORPORATION OF NEW YORK.

DESIGN FOR AN ELECTRIC-LIGHT FIXTURE.

Application filed December 4, 1926. Serial No. 19,928. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for Electric-Light Fixtures, of which the following is a specification, reference being had to the accompanying drawings, forming part thereof.

In said drawings:

Figure 1 is an elevation of an electric light fixture showing my new design.

Figure 2 is a bottom plan view of the same, partly in detail and partly in outline, the part shown in outline involving repetition of the detail.

I claim:

The ornamental design for an electric light fixture, as shown.

CHARLES W. LOGAN.
